Int. Cl. D8—08

U.S. Cl. D8—243

FIG. 1 is a perspective view of a sign mounting bracket embodying my new design; the broken line portions of FIG. 1 are for illustrative purposes only.

The side not shown is identical to that shown in the single perspective view, the bottom having a conventional tubular opening.

I claim:

The ornamental design for a sign mounting bracket, as shown and described.
